UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

SPRING-CHUCK.

968,051.

Specification of Letters Patent. Patented Aug. 23, 1910.

Application filed March 8, 1907. Serial No. 361,260.

To all whom it may concern:

Be it known that I, BENGT M. W. HANSON, a citizen of Sweden, residing at Hartford, in the county of Hartford and State of Connecticut, have invented certain new and useful Improvements in Spring-Chucks, of which the following is a specification.

This invention relates to chucks of a kind having a face-plate slotted to produce a series 10 of segments or sections and having an inclined periphery coöperating with a reverse incline on the inner wall of a recessed head carried by the chuck-spindle, said face-plate being drawn within the head to effect compression of the segments.

Primarily the object of the invention is the provision in connection with a face-plate having resilient sections or segments of work-clamping-jaws, one for each segment, 20 and means whereby said jaws may be adjusted toward and from the axis of the chuck-spindle.

Other objects of the invention are the provision of improved details of construction, as will be hereinafter explained.

In the accompanying drawings, Figure 1 is a longitudinal vertical section of one form of the improved chuck. Fig. 2 is a front end view. Fig. 3 is a transverse vertical 30 section on line 3, 3 of Fig. 1. Fig. 4 is a longitudinal vertical section of another form of the improved chuck. Fig. 5 is an end view of Fig. 4. Fig. 6 is a view partially in section and in elevation of another form 35 of construction, and Fig. 7 is a front view of Fig. 6. Fig. 8 is a section on line 8—8 of Fig. 1, looking in the direction of the arrow, and Fig. 9 is a partial sectional detail on line 9—9 of Fig. 8.

Like numerals designate similar parts throughout the several views.

Referring to the drawings, the numeral 1 designates a chuck-spindle enlarged and externally-threaded at 2 at its forward end to receive a head 3 having an internally-threaded hub 4, and said head also having a recess 5 with an inclined peripheral wall 6 in its front part.

Designated by 7 is a face-plate, shown as 50 flat and as split at 8 into a series of segments 9, and having an inclined periphery 10 and a hub also split at 12 at right-angles to and in line with the slots 8 of the face-plate. In other words, the slots of the face-plate

are carried down and into the hub where 55 they terminate adjacent to the rear end thereof, as illustrated in Fig. 1. A chamber 14 is formed in the inner side of the face-plate, and in said chamber is placed a split-spring annulus 16 surrounding a ring 15, 60 said annulus serving normally by its spring-like action to expand the resilient segments, said expansion being limited by ring 15, which together with said annulus is held in place by pins 17. The ring 15 serves also 65 to protect the split face-plate 7 against possible injury while removed from the machine-spindle. In the split front of the face-plate are formed grooves or slots 18, for the reception of nuts 19, adjustable along 70 the same, said nuts being secured by bolts 20, the heads of which are received in recesses of chuck-jaws 21.

Designated by 22 is a pull-rod or jaw-actuating member having an inclined head 23, which fits within the tubular hub and bears against the inclined inner wall of the same, the stem of said pull-rod passing through a perforation 25 in the rear end of the hub, and the rod being prevented from 80 rotation by a pin 26 entering a recess in its head, as shown in dotted lines Fig. 1.

Designated by 27 is a cap having a chamber to receive the inner end of the spindle 1, said cap being slotted at 28, and perforated 85 in its walls at both ends. A perforated block 29 is fitted in the slot 28, is bifurcated at one end at 29' to receive a drive-pin 30, and is provided with a hook 31 at its opposite extremity through which an eccentric portion 90 32 of a bolt 32' passes, said bolt being prevented from longitudinal displacement by a screw 33 entering a groove 34. On its ends the bolt is provided with heads 35 suitable for the reception of a wrench. 95

Slipped over the rear threaded end of pull-bolt 22 is a washer 36, and in engagement with said threaded end is a nut 37, by turning which the pull-rod will be actuated to force the face-plate within the recess of 100 the head 3, and to cause the chuck-jaws thereof to engage an object to be held, after which a final powerful gripping action may be produced thereon by turning the eccentric-bolt 32. By releasing said nut and 105 eccentric bolt, the spring-like action of the segments 9 together with the expanding tendency of the split spring annulus 16 will

cause said segments to expand and withdraw said chuck-jaws. A dowel-pin 38 of the head 3 enters a hole in the face-plate and prevents it from independent rotation.

5 In the form of the invention illustrated in Figs. 4 and 5 the head 3 is replaced by one designated by 39, and differing but colorably from said head 3, and the spindle 40 is provided with a threaded boss or circular enlargement 41, the space between the end of the boss and the extremity of the spindle being filled by a conical sleeve 42, the face-plate is split in the same manner as in Fig. 1, and the slits 8 end in a hub 43 passing 10 through a sleeve 42', externally threaded to receive the internal threads of an operating tube 44, and the jaws 21 are replaced by jaws 45 of different formation. In other respects the parts are the same, work in the 15 same way, and are marked with like numerals.

20 In Figs. 6 and 7 the chuck-jaws 21 are actuated by screws 46 collared into perforations of the face-plate, and engaging nuts 47 of the jaws, said nuts traveling in the slots 18. In the detail view Fig. 9, the parts represented are the same as in Fig. 1.

25 From what has been stated it will be evident that in all forms of the invention shown, and in many other forms which could be illustrated, the principle of the invention is the same; that, therefore, changes may be made without departure from my invention; and that such invention is not 30 limited to any specific means for drawing in the split face-plate, nor to any particular form of chuck-jaws carried by the sections of said face-plate.

35 It will be obvious from what has been hereinbefore set forth that my improvements are especially applicable to what are known as "stepped chucks". A chuck of this type is of particular advantage in holding cylindrical or substantially cylindrical work during the grinding of one face and half the periphery thereof after the corresponding portions have been previously ground or otherwise operated upon. A stepped chuck is of prime utility where 40 the work to be held thereby is always of uniform size. Where with the ordinary chucks of the kind referred to, the same have to be altered as to size to meet the particular conditions of work this is not the 45 case with my improved chuck. It will be assumed that with the ordinary stepped chuck a piece of work is to be held thereby. In this event the jaws are first opened and thereafter closed upon said work to clamp 50 the same. Should it be necessary to operate upon a smaller piece of work this will not be possible while if the second piece of work to be held is still larger the work-receiving opening of the chuck has to be enlarged to 55 receive the same. It therefore requires but

a short time to render such ordinary chucks useless and they therefore must be discarded. In other words there is no positive provision for adjustment and if they are to be enlarged they are practically spoiled 70 or ruined. Practically therefore the customary stepped chuck will only hold one size of work and its use to receive different sizes of work is so costly as to be practically prohibitive. The contrary is the case with 75 my chuck which possesses every advantage that the ordinary stepped spring chuck has with the extra advantage of adjustability at a very trifling cost. It should be stated that a stepped spring chuck is a very expensive tool although this is a very well known fact. I provide a part having resilient sections which removably receive bodily adjustable jaws. These jaws can be moved toward or from the axis of the chuck 80 to meet the different conditions, being of course ground along their operative faces to adapt them to the diameter of the work. In time these removable jaws become useless; they can be cast aside as they cost only a 85 few cents. In this connection I deem it desirable to refer to the method of using my chuck. The jaws 45 are first adjusted either inward or outward as the case may be until their working portions bound a circle which 90 is smaller in diameter than the size of work to be clamped thereby. A stick of wood or other article is then inserted into the central opening of the face plate 7 following which the sections 9 are constricted as hereinbefore 95 set forth; this results in firmly holding the jaws in their adjusted positions. When this is concluded the working portions of the jaws can be cut away, reduced or ground 100 until the circle bounded by said jaws or working portions thereof equals in diameter 105 that of the work. The pressure on the jaws will then be relieved by freeing said sections 9 subsequent to which the work will 110 be introduced into said jaws and finally the latter will be closed upon the work by the second constriction of said resilient sections 9.

115 Having thus described the invention, what I claim is:

1. A chuck having jaws, an endwise movable pull-rod constituting a jaw-actuating member, a spindle through which said rod extends, a cap closing the outer end of said spindle and having a chamber to receive 120 said rod, a rocking member supported by said cap, a nut threaded on the outer end of the rod and engaging against said rocking member, and a cam supported by the cap 125 for operating said rocking member and thereby the nut to impart an outward thrust to said pull-rod.

2. A chuck having jaws, an endwise movable pull-rod constituting a jaw-actuating member, a spindle through which said rod 130

extends, a cap closing the outer end of the spindle and having a chamber to receive said rod, a rocking member supported by said cap and through which said rod extends, a nut threaded on the outer end of the rod and bearing against the rocking member, and a bolt supported by said cap and having a cam portion to swing said

rocking member, the latter having a recess to receive said cam portion.

10

In testimony whereof I affix my signature in presence of two witnesses:

B. M. W. HANSON.
